Attorney

UNITED STATES PATENT OFFICE.

FRANK NOVESS, OF YPSILANTI, MICHIGAN.

FENCE-POST.

1,271,751.

Specification of Letters Patent.

Patented July 9, 1918.

Application filed August 22, 1917. Serial No. 187,705.

To all whom it may concern:

Be it known that I, FRANK NOVESS, a citizen of the United States, residing at Ypsilanti, in the county of Washtenaw and State 5 of Michigan, have invented certain new and useful Improvements in Fence-Posts, of which the following is a specification, reference being had to the accompanying drawings.

10 This invention relates to fence posts, and particularly to posts designed to support a fence at the end of the fence line, or to support a gate, the post being particularly adapted for supporting gates.

15 One object of my invention is to provide a post of this character which is adjustable at all times and from all angles.

Another object is to provide a fence post which can be set up or taken down at will 20 and which cannot sag or lean under the weight of the gate.

A further object is to provide a post of this character which can be set up, or taken down, or adjusted, without injury to its base 25 or other parts.

A further object is to provide improved means for bracing the post against sagging.

Other objects will appear in the course of the following description.

30 My invention is illustrated in the accompanying drawings, wherein:—

Figure 1 is a perspective view of a fence post constructed in accordance with my invention;

35 Fig. 2 is a side elevation of the post, the base being shown in section and the brace being shown partly in section and partly in elevation;

Fig. 3 is a section on the line 3—3 of

40 Fig. 2;

Fig. 4 is a section on the line 4—4 of Fig. 2; and

Fig. 5 is an underside plan view of the member 24.

45 Referring to these drawings, 10 designates the base upon which the post is mounted, this base being preferably of cement and being T-shaped in plan, this base being formed with a socket in the head of the T for the reception of the post 11. The post 50 11 is of iron pipe and is disposed within the socket. The post at its lower end carries an anchor plate 12, which is fastened by bolts 13 to the concrete base. From one of these 55 bolts extends an adjusting rod 14, which passes through an adjusting block 15 and is

provided with a nut 16. This adjusting block 15 is slidably mounted upon the base 10 and has an upwardly and inwardly extending stud 17. A lock pin 12^a extends 60 through the post and locks in a groove in plate 12.

Mounted upon the post 11 is a semi-circular collar or abutment member 18, which partly embraces the post and which is 65 formed with an inclined face 19 having a projecting stud 20, confronting the stud 17. A tubular brace 21 is adapted to be disposed in engagement with the studs 17 and 20 as illustrated in the drawing. The collar 18 70 is held to the post in any adjusted position by means of a U-shaped bolt 22, the collar being formed with an overhanging flange 23 around which the U-bolt passes. It will be obvious now that by tightening up on the 75 bolt 16, the block 15 may be shifted to thus brace the post and hold it in any desired position.

Disposed around the post and above the collar 18 is an adjusting plate 24 somewhat 80 elliptical in shape and having a central aperture fitting the pipe which forms the post. The under face of this plate at its ends is formed with downwardly extending lugs 25, having flat transverse inner faces 85 26, and at one end of each of these lugs 25 there is formed a downwardly extending shoulder 27. The ends of the plate are bored as at 28 for brace rods 29. These brace rods extend downward in divergent 90 relation and at their lower ends are formed with hooks engaging in eyes 30 embedded in the cement base. The upper ends of the rods are provided with nuts 31, whereby the rods may be placed under tension. It 95 will be noted from Fig. 4 that the plate 24 is disposed on top of the collar 18, the thickened portions 18^a at the sides of the collar are disposed immediately behind the shoulders 27, the bolts 29 passing down just 100 at the sides of these thickened portions so that the plate and the collar are to a degree interlocked.

A gate post constructed in accordance with this invention may be readily adjusted 105 by adjusting the block 15 so as to hold the post at any desired angle, and then the post may be held from any sagging movement by tightening up upon the braces 29, until the post is thoroughly braced from movement 110 in any direction. It will also be seen that the post can at any time be adjusted and

that it can easily be set up or taken down. Furthermore the post may be readily adjusted or the whole post taken down, without injury to the base or any of the parts of the post. The angle of the post may be readily controlled by a turning up on the nut 16 or a relaxing on this nut.

Having thus described my invention, what I claim is:—

- 10 1. A structure of the character described including a base having a socket, a post inserted in the socket, a collar detachably mounted on the post and adjustable therewith; a block mounted on the base and adjustable toward or from the post, a brace extending from the block to said collar, a plate through which the post passes, and resting upon said collar and having interlocking engagement therewith to prevent a rotation of the collar, and downwardly divergent rods connected at their lower ends to the base and passing through the ends of the plate and provided with nuts whereby said plate may be drawn down upon the collar.
- 15 2. A fence structure of the character described comprising a base having a socket in its head, a tubular post disposed in said socket, a collar mounted upon the post and vertically adjustable thereon and having a downwardly and outwardly inclined stud, a block slidably mounted on the base and having an upwardly and inwardly inclined stud, a brace disposed between said studs, a

plate attached to the head of the base, an adjusting rod operatively connected to the plate and extending through the block and having a nut bearing against said block to thereby adjust it, a plate having an aperture for the passage of the post and resting upon the top of the collar and extending laterally beyond the collar and having interlocking engagement therewith to resist rotation of the collar, downwardly divergent brace rods, their upper ends of which pass through the ends of the plate and are provided with nuts, and eye-bolts with which the lower ends of the brace rods engage.

3. A structure of the character described including a post, a collar detachably mounted on the post and vertically adjustable therewith, a brace extending upward at an inclination and engaging said collar to resist a movement of the post in the direction of the brace, a plate through which the post passes resting upon the collar and having interlocking engagement therewith to prevent a rotation of the collar independently of the plate, and downwardly divergent bolts passing at their upper ends through the plate and having nuts at their upper ends engaging with the plate.

In testimony whereof I hereunto affix my signature in the presence of two witnesses.

FRANK NOVESS.
